CLAIM

The ornamental design for a deployable building, as shown and described.

DESCRIPTION

FIG. 1 is an end perspective view of a deployable building, shown in a compact configuration;

FIG. 2 is an end perspective view in a partially deployed (floors deployed) configuration;

FIG. 3 is an end perspective view in a partially deployed (floors and sides deployed) configuration;

FIG. 4 is an end perspective view in a deployed configuration;

FIG. 5 is an end perspective view in a partially deployed hurricane-safe configuration;

FIG. 6 is an end perspective view in a hurricane-safe configuration; and,

FIG. 7 is a plan view corresponding to FIG. 4.

The broken lines depict environment and form no part of the claimed design.
